UNITED STATES PATENT OFFICE.

WALDEMAR KOPS, OF NEW YORK, N. Y., ASSIGNOR TO KOPS BROS., OF NEW YORK, N. Y.,
A FIRM.

ELASTIC FABRIC.

1,024,207.

Specification of Letters Patent.

Patented Apr. 23, 1912.

Application filed September 27, 1911. Serial No. 651,549.

To all whom it may concern:

Be it known that I, WALDEMAR Kops, a citizen of the United States, residing in the borough of Manhattan, in the city, county, and State of New York, have invented an Improvement in Elastic Fabrics, of which the following is a specification.

My invention relates to elastic fabric or webbing of parallel sided or tapering form and to the method of weaving the same, with the object of providing an elastic fabric suitable for use between parts under tension and in the gores of corsets, slippers, etc., and wherever such forms of elastic fabric are useful in the arts and manufactures.

In the article of my invention I provide opposite borders or edges of in-elastic fabric forming sewing sections by which the fabric is securely connected and anchored in place where used and between these sewing sections is an elastic part adapted to yield under the tension of use. The elastic part comprises warp threads, a minimum number of weft threads and elastic strands at an opposite angle to the warp threads, with their respective ends woven in and held by a part of the in-elastic fabric margins or sewing sections. The elastic part may be parallel sided in a parallel sided fabric, or tapering in a tapering or parallel sided fabric.

I prefer to employ for the elastic section an endless elastic strand preferably having a braided or twisted cover of threads of suitable material and to weave this endless elastic strand preferably under tension back and forth with doubled ends through the elastic section, the doubled ends being, for an appreciable length or to the selvage woven into the in-elastic marginal or sewing sections so as to anchor the same in effectually for the strain and tension applied to the elastic section in use.

The elastic fabric of my invention may be woven continuous of any width and thereafter cut up. It may be parallel sided or in tapering sections. Where there are tapering sections the same may be woven in reverse interlocking series and substantially endless, adapted thereafter to be cut up into sections for use in gores of corsets, slippers, etc.

In the drawing, Figure 1 is a plan of a parallel sided elastic fabric formed accord-

ing to my invention. Fig. 2 is a longitudinal section at the dotted line $x-x$ of Fig. 1 in larger size. Fig. 3 is a cross section in larger size at the dotted line $y-y$ of Fig. 1. Fig. 4 represents by a plan a section of tapering elastic fabric with a V shaped elastic part and the doubled ends of the elastic extending to near the selvage. Fig. 5 is a diagrammatic plan illustrative of the method of manufacturing the tapering section of Fig. 4 in reversed interlocking series of any width and length. Fig. 6 is a plan of a parallel sided elastic fabric like Fig. 1 except in this case the elastic strands extend to the selvage. Fig. 7 shows a parallel sided elastic fabric with a V shaped elastic part and Fig. 8 shows the V shaped elastic part with parallel sided sewing sections.

Similar letters and numerals of reference in the several figures indicate the same parts.

The elastic parts in Figs. 1, 4, 5, 6, 7 and 8 are shown as woven under tension of the elastic strands.

a and a' represent the inelastic marginal parts, and b the elastic parts. All of said parts a and a' and b are formed with warp threads of suitable material and with a minimum of weft threads. The parts a and a' are also formed with additional weft threads or filling of suitable material. The parts b preferably contain only the warp threads, a minimum number of weft threads and the elastic weft threads, and the stretch of the elastic strands is at right-angles to the warp threads and to the woven selvage of the webbing.

I may employ weft threads of cotton or suitable materials with the elastic weft or filling threads, and I may apply appreciable tension to the elastic strands with the movement of the shuttle in the weaving operation, but I do not limit my invention in this respect.

Figs. 1 and 6 illustrate that my invention may be embodied in a parallel sided webbing. Fig. 7 illustrates that the invention may be embodied in a parallel sided webbing with a V shaped elastic part, and Figs. 4, 5, and 8 illustrate that the invention particularly considered may be embodied in a V shaped part or member, where the opposite edges have sewing sections with substantially parallel edges, the elastic section b intermediate thereof being

2
also V shape, and with this latter form it matters little whether there be a selvage to the parts α α' or not, for the forms just considered and illustrated by Figs. 4, 5 and 8 5 are specially adapted for the gores of corsets, slippers, etc., where a binding is put at the severed ends to prevent raveling of the threads and where the outer edges of the in-elastic marginal parts or sewing sections 10 are sewed into opposite edges of the gores and edges covered.

The forms illustrated in Figs. 1, 6 and 7 are particularly applicable where there are 15 parallel edges between and connected to which the elastic and in-elastic sections are to be connected. Fig. 5, diagrammatically considered, illustrates a manner of weaving the section shown in Fig. 4 or Fig. 8 wherein in the said sections are woven reversed to 20 be severed along their broad and narrow lines and also woven into interlocking series to be severed at the centers of the sewing or in-elastic sections α α' .

I may, if desired, extend the rubber weft 25 threads entirely across the width of the woven sections, as shown in Figs. 6, 7, and 8.

In Figs. 1, 4 and 5, the number of warp threads is shown as increased in the in-elastic sewing sections while in Figs. 6, 7 and 8, 30 the number of warp threads and also the number of weft threads is increased in the inelastic sewing sections, but I do not limit myself in these respects.

I claim as my invention:

35 1. An elastic fabric woven with warp threads of suitable material and a rubber thread or strand as weft, or filling and a certain pre-determined portion of the warp woven with an additional filling of suitable 40 material so as to produce one or more in-elastic sections.

2. An elastic fabric woven with warp threads of suitable material and a rubber thread or strand as filling or weft, and 45 binding a certain pre-determined portion of the warp threads, and an additional filling of suitable material binding the remainder

of the warp threads so as to produce an elastic webbing with in-elastic sections.

3. An elastic fabric woven with warp 50 threads of suitable material and a rubber thread as weft or filling throughout the width of the fabric, and additional filling threads of suitable material binding certain pre-determined warp threads so as to produce one or more non-elastic sections. 55

4. A flat strip elastic fabric, comprising an elastic center of elastic weft and in-elastic margins or sewing sections.

5. A flat strip elastic fabric comprising 60 in-elastic or sewing section margins and a central elastic section, the latter formed of warp threads and elastic weft or filling threads.

6. A flat strip elastic fabric, comprising 65 a V shaped center of elastic weft and in-elastic margins or sewing sections.

7. A flat strip elastic fabric comprising 70 in-elastic or sewing section margins and a central elastic section, the latter formed of warp threads and elastic weft or filling threads, and the elastic strands formed from a continuous piece of elastic doubled back and forth upon this and the doubled ends woven appreciably into the adjacent edges 75 of the in-elastic or sewing sections.

8. A flat strip elastic fabric comprising a V shaped elastic center and parallel sided in-elastic margins or sewing sections.

9. A flat strip elastic fabric comprising a 80 V shaped elastic center and parallel sided in-elastic margins or sewing sections, and in which the elastic strands are at right angles 85 to the warp threads and extend across the elastic center and into the parallel sided in-elastic margins or sewing sections for anchorage.

Signed by me this 14th day of September, 1911.

WALDEMAR KOPS.
